UNITED STATES PATENT OFFICE.

SAMUEL E. LOGAN, OF ANNISTON, ALABAMA, ASSIGNOR OF ONE-HALF TO WILLIAM A. FARRELL, OF JACKSONVILLE, ALABAMA.

FLUSH CAR-DOOR.

1,176,381.

Specification of Letters Patent. Patented Mar. 21, 1916.

Application filed August 7, 1915. Serial No. 44,309.

To all whom it may concern:

Be it known that I, SAMUEL E. LOGAN, a citizen of the United States, residing at Anniston, in the county of Calhoun and State 5 of Alabama, have invented certain new and useful Improvements in Flush Car-Doors, of which the following is a specification, reference being had to the accompanying drawings.

- 10 This invention relates to certain improvements in flush car doors, and it is an object of the invention to provide a door of this general character which is flush with the outer surface of the side of the car when in 15 closed position, and which effectively serves to render the door opening spark proof so that the possibility of the contents of the car becoming ignited is substantially entirely eliminated.
- 20 The invention consists in the details of construction and in the combination and arrangement of the several parts of my improved flush car door whereby certain important advantages are attained and the 25 device is rendered simpler, less expensive and otherwise more convenient and advantageous for use, all as will be hereinafter more fully set forth.

The novel features of the invention will be 30 carefully defined in the appended claims.

In order that my invention may be the better understood, I will now proceed to describe the same with reference to the accompanying drawings, wherein—

35 Figure 1 is an elevational view illustrating a car door constructed in accordance with an embodiment of my invention and in closed position, the coacting side of the car being shown in fragment; Fig. 2 is a vertical sectional view taken through the device as disclosed in Fig. 1; and Fig. 3 is a view similar to Fig. 2 but illustrating the door in an inoperative adjustment.

40 As disclosed in the accompanying drawings, 1 denotes a side of the car having the door opening 2 produced therein, the walls of the opening being stepped, as at 3, to afford a shoulder against which the door D is adapted to abut, said door being insertible 45 within the door opening from the outer side of the car and adapted to have its outer face flush with the outer face of the side when in applied position.

45 4 denotes a track-way arranged above the 50 opening 2 and disposed longitudinally of the

side 1 and on which is mounted the carrier 5 and said carrier is provided adjacent its extremities with the depending strap 6, the lower extremities of each of said straps being bent backwardly to afford a guide 7 co-acting with the depending flange 8 of the track-way, said track-way being substantially T-shape in cross section. The carrier is also provided with the rollers 9 adapted to engage the track-way inwardly of the 65 upper flange 10.

Pivotaly engaged with the door D adjacent its upper extremity are the yokes 11 substantially U-shape in form and herein disclosed as formed from a single length of 70 material, said yokes being pivotaly engaged with the lower ends of the straps 6. The lower edge of the door D is provided with the recesses 12 in which are adapted to be disposed the rock arms 14 carried by the 75 rock shaft 15 mounted for axial movement upon the outer face of the side 1 at a point below the opening 2 and the intermediate portion of said rock shaft 15 is provided with the operating lever 16 whereby it will 80 be perceived that the door D may be readily forced within the opening 2. It is to be noted that the bottoms of the recesses 12 are formed into the cam surfaces 12^a whereby the contact of the arms 14 therewith serves 85 to elevate the door D and to force the same snugly within the door opening 2 and it is to be further noted that the lower slot of the door opening 2 is provided with the cut out portions 14^a to offer no obstruction to 90 the requisite rocking movement of the arms 14. The arms 14 also afford a means whereby said door may be maintained in closed position and for this purpose the lever 16 is provided with the slot 17 to receive the 95 staple 18 carried by the door and the free extremity of the lever 16 is provided with the locking member 19 pivotaly engaged therewith and disposed on such a curvature as to be directed through the staple 18 to 100 maintain the lever against outward movement relative to the door.

Projecting outwardly from the side 1 are the brackets 20 which serve to prevent undue outward swinging movement of the door D 105 when in inoperative position and the side 1 is also provided with a bracket or stop 21 positioned midway of one of the vertical edges of the opening 2 and serving to limit the movement of the door D so as to assure 110

its proper positioning relative to the opening 2 so that the arms 14 may be properly engaged with the door for forcing the same in closed adjustment. I also find it of advantage to have disposed across the upper end of the door the narrow strip 22 which serves to prevent the upper portion of the door D from moving outwardly and thereby assuring a proper seating of the door within the opening 2. The lower end portion of the door is provided with the loops 23 to afford a medium whereby the door may be manually operated.

From the foregoing description, it is thought to be obvious that a flush car door constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

23 I claim:—

1. In combination with a wall having an opening therein, a track-way disposed above the opening, a carrier mounted upon the track-way, a door seatable within the opening, a linked connection between the door

and the track-way, the lower edge of the door being provided with recesses, the bottom of said recesses being provided with cam surfaces, a rock shaft supported by the door below the opening, arms carried by the shaft adapted to extend within the recesses of the lower edge of the door and engageable with the cam surfaces thereof for raising the door within the opening in the wall and for maintaining the door therein, and means for rocking the rock shaft.

2. In combination with a wall having an opening therein, a track-way disposed above the opening, a carrier mounted upon the track-way, a door seatable within the opening, a linked connection between the door and the track-way, the lower edge of the door being provided with recesses, the bottom of said recesses being provided with cam surfaces, a rock shaft supported by the door below the opening, arms carried by the shaft adapted to extend within the recesses of the lower edge of the door and engageable with the cam surfaces thereof for raising the door within the opening in the wall and for maintaining the door therein, means for rocking the rock shaft, and a narrow strip disposed across the upper end of the opening to afford a seat to receive the upper end of the door.

25 In testimony whereof I hereunto affix my signature in the presence of two witnesses.

SAMUEL E. LOGAN.
